UNITED STATES PATENT OFFICE.

FRANCIS E. KING, OF HUNTINGTON, WEST VIRGINIA.

RAIL JOINT.

Application filed March 24, 1927. Serial No. 177,894.

My invention relates to rail joints. My object is to provide a construction which dispensing with bolts will be capable of inexpensive manufacture, easy of use, and will 5 make a thoroughly dependable connection between the rails.

My invention consists in whatever is described by or is included within the terms or scope of the appended claims.

10 In the drawings:

Fig. 1 is a top plan view partly in section illustrating an embodiment of my invention;

Fig. 2 is a cross section on the line 2—2 15 of Fig. 1; and

Figs. 3 and 4 are, respectively, elevations of opposite sides.

Referring in detail to what is shown in the drawings, it will be seen that my device 20 comprises a main member in the form of a plate, 10, which may be roughly described as L-shape in cross section, the vertical arm of the L, when in position, extending between the underside of the rail-head downward alongside the web and over the rail flange on the same side of the rail so that its shape corresponds with that of the adjacent portions of the rail, and the horizontal arm 25 of the L being extended beneath the base of the rail to the opposite side and being carried beyond the opposite side with a vertical jog, 11, upwards at the edge of the rail, such jog forming a shoulder to engage the adjacent edge of the rail base, and thus the 30 rail base being engaged on opposite edges, lateral displacement is prevented. Upon the portion of the horizontal arm projecting beyond the rail is placed a clamp, 12, in the form of a narrow plate or bar, which in what 35 I now consider the best form of my invention is pivotally connected to such portion of the horizontal arm by a rivet, 13, so that said clamp bar may be swung from a position extending parallel with the rails (as indicated in dotted lines in Fig. 1) to a position 40 at right angles thereto and overlapping or lying upon the adjacent rail flanges at the joint between the rail ends, so that it overlaps the flanges of both rails at the joint, 45 as shown in full lines in Fig. 1. The clamp bar has beyond the pivot a downwardly projecting crimp or off-set, 14, situated to engage the adjacent edge of the horizontal arm of the member, 10, when the clamp is in 50 clamping position, and thereby is held from accidental displacement. There is, of course,

enough "give" or yield to allow the movement of the crimp over the adjacent surface of the horizontal member in turning the clamp bar between the two positions shown 60 in the drawings.

For engaging the rail holes to secure the rails against longitudinal movement, the vertical arm of the member, 10, has in position to enter the rail holes, horizontally projecting lugs, 15, one for each hole, which are inexpensively formed by punching out from the vertical arm of the member, 10. Thus, I provide a very inexpensive and yet satisfactory substitute for bolts that are commonly used for the fish or tie plates of rail joints. 70

It will be seen that although my joint comprises three parts counting the rivet, yet for all practical purposes, it is a single or one-piece member or unit for the parts assembled 75 remain assembled, so that there are no loose or separate pieces that must be separately taken care of, and the workman in making the joint has to deal with but one member or unit. For applying the device to connect two 80 rails, the workman needs no other tool than a hammer. It will thus be seen that in application, as well as in manufacture, expense is reduced to the minimum.

Because of the extended surface contact 85 between the rail ends and the plate, no bonding of the rail ends is necessary, and thus economy of road construction is contributed.

My joint is especially useful in mines, and when steel mine ties are used, my joint may 90 be permanently attached to the ties, so that tie and joint would then be a complete member.

What I claim is:

1. A rail joint comprising a substantially 95 L-shape member with portions to lie against the side of the rail and beneath and beyond the rail on the opposite side provided with integral lugs to enter the rail holes, said lugs being struck out of the portion of the 100 plate at the rail side, and a clamp adapted to extend between such member and the rail flange on the upper side, said clamp being a bar permanently pivoted to said member.

2. A rail joint comprising a substantially 105 L-shape member with a vertical portion adapted to lie against the rail side and having rail hole entering projections, and a horizontal portion adapted to extend beneath the rail to and beyond the opposite 110 side thereof, and a rail engaging clamp bar pivoted to such horizontal portion and mov-

able on its pivot between positions parallel with the rails and crosswise thereof.

3. A rail joint comprising a substantially L-shape member with a vertical portion adapted to lie against the rail side and having rail hole entering projections, and a horizontal portion adapted to extend beneath the rail to and beyond the opposite side thereof, a rail engaging clamp bar pivoted to such horizontal portion and movable on its pivot between portions parallel with the rails and crosswise thereof, and means to hold said clamp bar from accidental movement.
4. A rail joint comprising a member with portions to reach over the rail flange on one side and lie against the side of the rail and beneath and beyond the rail on the opposite side, and a clamp bar pivoted to said portion that extends beyond the rail and adapted to overlap the adjacent rail flange on the upper side, said member having between the clamp bar pivot and the rail base a jog that is en-

gaged by the adjacent edge of the rail base and forms a bearing to sustain lateral thrust 25 from the rail.

5. A rail joint comprising a substantially L-shape member with a vertical portion adapted to lie against the rail side and having projections to enter holes in the rail, and a horizontal portion adapted to extend beneath the rail base and having a rail edge engaging jog from which such portion extends outward and a clamp upon such outwardly projecting portion adapted to overlie the top 35 of the rail base, said jog forming a bearing with which the adjacent edge of the rail contacts to resist lateral thrust on the side where the clamp is situated, said jog being formed by carrying said outwardly projecting portion to a higher plane than the portion of the L-shape member directly beneath the rail base.

In testimony whereof I hereunto affix my signature.

FRANCIS E. KING.
